(57) **CLAIM**

The ornamental design for an electrosurgery handpiece, as shown and described.

DESCRIPTION

FIG. 1 is a top perspective view of the electrosurgery handpiece of the present invention;

FIG. 2 is a bottom perspective view thereof;

FIG. 3 is a top view thereof;

FIG. 4 is a bottom view thereof;

FIG. 5 is a side elevational view thereof;

FIG. 6 is a rear elevational thereof;

FIG. 7 is a front elevational view thereof;

FIG. 8 is a top perspective view of the electrosurgery handpiece of the present invention shown connected to a vacuum tube and an electrical cord both shown in phantom; and,

FIG. 9 is a bottom perspective view of the electrosurgery handpiece of the present invention shown connected to a vacuum tube and an electrical cord both shown in phantom. The phantom lines shown in the FIGS. 8 and 9 are illustrative of environmental structure only and form no part of the claimed design.
